(57) **CLAIM**

The ornamental design for an “oxygen tank key,” as shown and described.

DESCRIPTION

FIG. 1 is a front elevational view of an “oxygen tank key” showing my new design;

FIG. 2 is a top plan view thereof;

FIG. 3 is a rear elevational view thereof;

FIG. 4 is a bottom plan view thereof;

FIG. 5 is a right side elevational view thereof, the left side being identical thereto; and,

FIG. 6 is a perspective view thereof.

The broken lines in FIG. 4, which define the bounds of the claimed design, form no part thereof.
